AERIAL PASSENGER TRAMWAY

Waldemar I. Bendz, Arlington, Mass., assignor to
 Westinghouse Electric & Manufacturing Company, East Pittsburgh, Pa., a corporation of Pennsylvania

Application February 18, 1939, Serial No. 257,171

13 Claims. (Cl. 177—336)

This invention relates to tramway control systems, and is particularly directed to a system in which a car is moved through a predetermined path from one terminal position to a second terminal position, by means of a traction cable to which power is imparted through a motor driven sheave.

Because of the nature of the drive involving the transmission of power from the sheave to the traction rope, or cable, solely by the friction between the cable and the sheave, there may be a certain amount of slippage between the sheave and the traction rope. An indicator, that is provided to show the position of the traveling car, is usually also driven from a shaft that is mechanically connected to the sheave. Consequently, when slippage occurs between the sheave and the traction rope, the position of the indicator for the car will not correspond to, or be synchronous with, the position of the car and the indication given by the position indicator will therefore be false.

In the tramway system to which my present invention is applied, the passenger car travels along a supporting cable which is suspended between supports a considerable distance apart. Consequently, the car does not assume a definite position either vertically or horizontally within limits of position which are sufficiently close to permit the operation of a limit switch of the track type or so-called hatchway type. This is due to the fact that the vertical position of the car is variable, depending upon the load of the car and the sag of the cable, which may also be variable depending upon temperature as well as weight of the car and passengers. The horizontal position of the car is also variable due to wind and the unbalanced loading in the cars. Consequently, the usual form of limit switch of either of the types mentioned is not applicable to a drive of this type. While limit switches cannot be properly located to obtain the necessary number of slow-down points prior to a definite stop for the reasons as named above, it happens that the cars are carefully guided during the last few feet of travel so as to properly position the car for unloading of passengers.

In the present system, I employ a limit switch to be controlled by the car to aid in correcting the position of the indicator; and also employ the indicator, if desirable, to provide slow-down control for the main motor.

The primary object of my invention, therefore, is to provide a system that will automatically correct any deviation of the position indicator, when it deviates from a proper position corresponding to the position of the car, because of slippage between the sheave and the traction rope.

In the accompanying drawings,

Figure 1 is a simple operating and control system arranged to operate in accordance with the principles of my invention;

Fig. 2 is a diagrammatic view showing the general disposition of the tramway system to which my invention has been applied: and

Fig. 3 is a simple operating and control system embodying a modification of my invention.

As shown in the diagram in Fig. 1 a main power motor 1 for the tramway system is arranged to be energized from a power circuit 2. The motor 1 drives a sheave 3 through appropriate reduction gearing 4. The sheave 3 is of the usual grooved pulley form and is arranged to drive a traction cable or rope 5 by friction. The traction cable 5, as illustrated in this application, operates substantially as an endless cable, in such manner that one portion 6 of the cable moves a tram car 7 in one direction, while an adjoining portion 8 of the cable will move a second tram car 9 in the opposite direction.

It will be understood, of course, that instead of an endless cable an equivalent system might be employed in which the two ends of the cable would be controlled to impart the proper direction of movement to reel in one end of the cable while paying out the other. Also, instead of an endless cable system on which two passenger cars are fastened, an equivalent system might be employed using only one car which is made to travel back and forth between two terminal positions. In either system the passenger car or cars may be replaced by a device or devices for carrying freight or other form of material.

Where two cars or devices are used, the system is a double reversible tramway. Where one car is used, the system is a single reversible tramway.

As shown in the drawings, the two tram cars will be alternately moved from one of their respective terminal positions to the other of their respective terminal positions. In order to provide the reversing movement to the cable, the motor 1, which is shown as a shunt-wound direct current motor, is reversely energized by reversely connecting the field winding 11 to the main power circuit 2 through either of two switches 12 or 13. The switches 12 and 13 are, in turn, selectively controlled by a controller switch 14 that is illustrated for simplicity as a single-pole double-throw switch. The armature circuit is illustrated as passing through contact members on either switch 12 or 13 so the motor circuit will be opened, as both switches 12 and 13 are de-energized, when the master switch 14 is thrown to neutral position.

In order to slow down the main motor 1 as the tram cars 7 and 9 approach their respective terminal positions, the motor circuit is appropriately controlled to reduce the motor speed. In

practice, the system actually employed for that purpose is a variable voltage direct current system, but, for the sake of simplifying the description, I have illustrated a simple system in which the armature circuit of the motor is provided with three resistors 15, 16 and 17 connected in series relationship, and the resistors are arranged to be progressively inserted into the armature circuit when the motor is to be decelerated, and conversely, to be shorted out of the armature circuit when the motor is to be accelerated from rest, in a manner and for a purpose that will be described below.

In order to indicate the respective positions of the tram cars 7 and 9, two position indicators 18 and 19 are provided. The position indicators are disposed upon threaded nuts 21 and 22 respectively mounted upon threaded lead screws 23 and 24, that are respectively driven by gears 25 and 26. The gears 25 and 26 are driven by a common driving gear 27 that is connected to the driven element 28 of a differential gear mechanism 29. The driving gear 31 of the differential mechanism 29 is connected through a suitable gear reduction 32 to the shaft 33 upon which the driving sheave 3 is connected.

In order to provide automatic or manual adjusting control of the position indicators 18 and 19, the differential mechanism 29 is provided with a driving gear 34 on the housing 35 of the differential mechanism 29. The housing 35 supports the two differential idler gears 36 and 37 that transmit motion from the driving gear 34 to the driven gear 28 of the differential mechanism.

In order to rotate the differential housing 35 by its gear 34, an auxiliary reversible motor 38 is provided that is disposed to rotate the housing 35 in either direction through a pinion 39, or to hold the housing 35 stationary to permit the differential operation of the differential mechanism.

When no slippage occurs between the driving sheave 3 and the traction rope or cable 5, the movement of the traction rope, and, consequently, of either tram car, will be attended by a corresponding proportional movement of the position indicators 18 and 19. The indicators will, therefore, occupy their respective terminal positions when the tram cars are at their respective terminal positions.

Because of the slippage, however, that occurs between the driving sheave 3 and the traction rope 5, due to the tension in the traction rope, which may be either positive or negative with respect to the torque of the driving sheave, the position indicators will, more often than not, not always be in a correct position corresponding to the position of the associated tram cars. In order to correct for such deviation of the position indicators from their proper positions due to cable slippage on the sheave, two limit switches 41 and 42 are provided and disposed adjacent the end or terminal positions of the path of each of the tram cars 7 and 9, respectively, so that the switches will be operated when the associated tram car moves to its ultimate position at a selected terminal. The limit switches 41 and 42, as controlled by their respective tram cars 7 and 9, are employed to set up and control the circuit of the auxiliary motor 38 for the differential mechanism 29.

In order to complete the control of the auxiliary motor 38, two other auxiliary switches 43 and 44 are provided, and they are disposed at the ultimate positions at selected terminal positions of the two indicators 18 and 19.

Thus, each tram car and its associated position indicator cooperate to control the auxiliary motor for the differential mechanism, to correct the position of the position indicator, if necessary, at the end of each tram car moving operation.

Energy for the auxiliary motor 38 is shown as derived from a three-phase supply circuit 45. The motor 38 is also provided with a friction solenoid brake 46 of the conventional type, which is released when its operating coils 47 are energized and which is set by springs, for example, when its operating coils 47 are deenergized.

When no electric power is applied to the auxiliary motor 38, the brake 46 is set, and, through the gear connection between the gear pinion 39 and the differential housing 35, locks the housing 35 against motion. While this condition exists, the differential acts as a straight one-to-one gear transmission to transmit rotation from the sheave shaft 33, through the gear reduction 32, to the driving gear 27 for the gears 25 and 26 to the lead screw gears 23 and 24.

When operation of the transmission is attended by no slippage between the sheave and the traction rope, each tram car will reach its terminal position at the same time as the corresponding position indicator reaches its terminal position. Under such condition no correction of the position indicators is required.

When conditions are such, however, that slippage does occur between the sheave and the traction rope, movement of the position indicators will not be proportional to and synchronous with the cable, and each position indicator will therefore not reach and occupy its correct relative position when its associated car reaches the terminal position. In order to correct for such deviation, the limit switch controlled by each car and the limit switch controlled by the associated position indicator are cooperatively connected, in series, to supply energy from the supply circuit 45 to the auxiliary motor 38, in the proper direction to rotate the housing of the differential mechanism, to operate the lead screws 23 and 24 a sufficient amount to restore the position indicators to the proper relative indicating positions.

The limit switch 41 controlled by the car 7 is provided with two contact members 48 and 49 to control the circuits of two conductors to the auxiliary motor 38. The switch 41 is normally biased to open position by a spring 50, and is arranged to be closed by a pivoted lever 51 that is located in such position as to be engaged, and moved to switch closing position, by the associated car 7 when the car is in its terminal position.

The limit switch 42 for the car 9 is similar to limit switch 41, and is provided with similar contact members 58 and 59 and a biasing spring 60 together with a control pivoted lever 61, corresponding to the same elements on limit switch 41.

A cooperating limit switch 43, that is controlled by the position indicator 18 at one terminal position, is also a double contact switch provided with two contact switches 53 and 54 that are normally biased to closed position by a spring 55. An operating button 56 is provided to be engaged and depressed by a roller 57 on the position indicator 18 to open the circuits between the two contact switches 53 and 54.

A limit switch 44, controlled by the position indicator 18 at its other terminal position, is pro-

vided with contacts 63 and 64, a biasing spring 65 and an operating push button 66 similar to those provided for the limit switch 43.

The limit switch 43 is disposed to be operated by the position indicator 18 at the left-hand limit of its travel, and the limit switch 44 is located to be operated by the roller of the position indicator 18 at the right-hand limit of its travel, at a position corresponding to the relative terminal or limit position of the position indicator 19. The operation of the two limit switches 43 and 44 by the position indicator 18 permits the position indicator 19 to be utilized for other control functions.

If no slippage has occurred between the sheave and the traction rope 5, while the car 7 has been raised from its lower terminal position to its upper terminal position, the position indicator 18 will move to, and be in, its proper relative terminal position to open limit switch 43 when car 7 reaches its upper terminal position to close the limit switch 41. Thus, although the circuit for motor 38 will be set up at the limit switch 41, it will be open at the limit switch 43 to keep the circuit open between the auxiliary motor 38 and its source of supply 45.

If, however, slippage has occurred between the sheave and the cable, due to an excessive loading of car 9, for example, so that the car 7 will reach its terminal position and close its limit switch 41 before position indicator 18 has been moved to its proper relative terminal position to open limit switch 43, limit switch 43 will still be closed when limit switch 41 is closed by movement of the car 7 to its upper terminal position. Indicator 18 will at that time occupy the dotted position A adjacent its proper relative terminal position above limit switch 43.

The energizing circuit is then closed from the supply source 45 through limit switch 43 of the position indicator 18, thence through limit switch 41 at car 7, to the brake coils 47 and to the auxiliary motor 38. As shown, the third conductor of the supply circuit 45 is connected directly to the motor. Consequently, the brake coils are energized to release the brake and the auxiliary motor is energized to rotate the case or housing of the differential mechanism. Since the main motor is now stationary, the sheave shaft 33 and the transmission unit 32 will be held stationary, and the rotation of the differential mechanism case will rotate the lead screws 23 and 24 until the position indicator 18 is moved to its proper relative terminal position where it will engage and open the limit switch 43. The circuit to the auxiliary motor will thereupon be opened and the brake restored to hold the auxiliary motor against further rotation.

When the main motor operation is reversed to lower the car 7, and to raise the car 9, the limit switch of car 7 will be opened, and, when car 9 reaches its upper terminal position, limit switch 42 will be closed. Limit switch 42 will cooperate with the position indicator switch 44 according to the position of the position indicator when the car 9 reaches its upper terminal position.

When the car 9 is in the proper terminal position, the position indicator will open its limit switch 44, if no slippage has occurred. If slippage has occurred, the position indicator will move to position B when car 9 reaches top terminal position. Limit switch 44 will be closed and will cooperate with car limit switch 42 to complete the circuit from the auxiliary supply source 45 to the auxiliary motor 38 to energize

and release the brake 46, and to operate the case or housing 35 of the differential mechanism 29. The connections to the auxiliary motor are now reversed, however, with respect to the connections made through the other set of limit switches, and the direction of operation of the auxiliary motor 38 is now reversed. The lead screws are now operated to move the indicator 18 from position B to its proper limit position to open limit switch 44.

Assume, instead, that car 9 is excessively loaded as compared to car 7, thus causing slipping and that car 9 is raised from the full line position to the dotted line position, at the latter position closing limit switch 42. The indicator 18 will have overtravelled to the right of limit switch 44 to a position C (indicated in dotted lines). Therefore, since both limit switches 42 and 44 are closed, a circuit will be completed through motor 38 which will effect a movement of the position indicator 18 to the right but which movement will be arrested by virtue of the fact that the threads of the lead screws 23 and 24 terminate just beyond the limit switches 43, 44 and just beyond switches 80 and 86 at which positions are located biasing springs 91, 92, 93 and 94 which urge the position indicator members in a direction toward the center of the lead screws. Therefore, as soon as the cars are moved in an opposite direction, that is, as soon as car 9 is moved from the dotted line position to the full line position, the position indicator 18 will be propelled to the left to approximately position A at which time limit switch 41 will close and owing to the fact that limit switch 43 is also closed, a circuit to motor 38 will be completed thereby effecting a correction of the position of indicator 18 (i. e., movement of indicator 18 to the left until it opens limit switch 43). In the event that instead of moving to a position A, the indicator again overtravels beyond the limit switch (this time, to the left of limit switch 43) no immediate correction will be afforded and none will be had until the position indicator is stopped somewhere between limit switches A and B. While this situation does permit inaccuracy of the position indicator, such inaccuracy is very small for one or a few round trips. The embodiment illustrated in Fig. 3, which will be described hereinafter, completely eliminates the above-described errors.

In order to decelerate the motor to permit slow landing of the cars at the upper terminals, the armature circuit of the main motor 1 is provided with the three resistors 15, 16 and 17 previously referred to. These resistors are progressively short-circuited as the cars move away from terminal position and are progressively inserted into the armature circuit as the car approaches and gradually moves into its final terminal position at the loading terminal.

I show these resistors 15, 16 and 17 merely to illustrate a simple system for establishing a gradual deceleration of the motor. In actual practice a variable voltage direct current system is employed to control the motor speed, but its description would unnecessarily enlarge this description of the operation of that part of the system.

In order to control the insertion and removal of these resistors 15, 16 and 17 into and out of the motor circuit, three short-circuiting contacts 71, 72 and 73 are employed for the respective resistors. The operating coils of the contacts 71, 72 and 73 are controlled by suitable

interlocking switches, of which switches 74, 75 and 76 are disposed adjacent one end of the path of travel of the position indicator 19, and switches 77, 78 and 79 are positioned adjacent the other end of the path of travel of the position indicator 19.

The short circuiting-contactors 71, 72 and 73 for the resistances are normally energized, to short-circuit the resistors 15, 16 and 17 when the system is being operated, until either car approaches its upper terminal position. At that time the appropriate interlock switches will be operated by the position indicator 19 to progressively open switches 73, 72 and 71 to deenergize the short-circuiting contactors and progressively and cumulatively insert the resistors 17, 16 and 15 in the armature circuit of the motor.

Conversely, as the cars move away from the upper terminal position, the position indicator 19 will progressively reset the interlock switches to reenergize the contactors 71, 72 and 73 to progressively short-circuit resistors 15, 16 and 17, in sequence, to permit the motor speed to gradually increase.

As schematically illustrated, each of the interlock switches 74 to 79, inclusive, is provided with a suitable actuator 80, and a toggle, or over-center, spring to hold the switch in the position to which it was last operated.

Each actuator 80, for the interlock switches 74 to 79 consists of an element provided with two arms 81 and 82 to be engaged by the roller 83 of the position indicator 19. When the roller engages the top arm 81, the switch is forced upwardly; when the roller engages the lower arm 82, the switch is forced downwardly. An overcenter toggle spring 85 is operated by the actuator 80 and serves to move the actuator and the switch to the extreme terminal positions of their path of movement, and to hold the switch in open or in closed position to which it has been moved.

When the toggle spring is moved by one arm of the actuator to move the actuator to its extreme position in one direction, the other arm for controlling movement of the switch to the other direction, is moved into the path of the roller, to be engaged by the roller when the indicator reverses and moves back in the opposite direction. The roller 80 engages either arm of the actuator and moves the switch against the associated spring, to open or to close the circuits at the contacts of the switch.

When indicator 19 moves from its extreme left position towards the right, switch 74 is operated to closed position, by the position indicator 19, to set up the circuits of all three operating coils of the contactors 71, 72 and 73. The circuit for contactor 71 is completed and contactor 71 operates to shunt resistor 15. As the position indicator 19 continues to move, however, it engages the lower arm of the actuator for switch 75, and moves switch 75 to closed position to close the circuit of the coil of contactor 72 and to set up the circuit for contactor 73. Contactors 71 and 72 will be held closed to short-circuit resistors 15 and 16.

As the position indicator 19 progressively moves to the right, its roller will engage the lower arm of the actuator of switch 76 and will operate switch 76 to closed position to close the circuit of the coil of contactor 73. When switch 73 closes, it short circuits resistor 17. The motor will then be energized with full voltage and accelerated to operating speed. The position

indicator 19 will continue to move in accordance with the movement of the tram system.

As the position indicator 19 approaches the other end of its path of travel, the switches 77, 78 and 79 will be similarly operated in sequence, and their associated contacts will be opened to deenergize contactors 73, 72 and 71, sequentially, to progressively insert the resistors 17, 16 and 15 into the circuit of the motor armature.

As shown in Fig. 1, for the purpose of illustration, switch 79 is in closed position. That is the position switch 79 would occupy just before the roller of indicator 19 would engage the upper arm of the actuator to move switch 79 to open position. It is also the position that switch 79 would occupy immediately upon reclosure, where the indicator 19 was started in operation from its extreme position, at the right, towards its terminal position at the left.

It will be observed that the actuators for the switches are reversely arranged in the two terminal groups, so that motion of the indicator toward either terminal position will open the switches, and motion of the indicator from either terminal position will reclose the switches.

By means of such an arrangement, or its equivalent, the speed of the main driving motor may be controlled according to the position of the car or cars of the system.

In addition, the proper relation between the cars or cars of the system and the position indicators is automatically established and maintained by the auxiliary motor, which corrects for any deviation during each cycle of operation.

Fig. 3 illustrates a modification of my invention in which there are two cars, 101 and 102, attached to an endless cable 103. The cable makes one or more turns around a driving sheave 104 and one of the cars is travelling up hill while the other car is travelling down. A driving motor 106 drives the sheave 104 through a suitable gear reduction 105.

The passenger cars travel up and down and are brought to a stop at passenger loading platforms at either end of the trip. An operator controls the movement of the cars and brings them to a proper stop at the loading platforms. This control of the car movement is manual under normal circumstances. However, in order to incorporate necessary safety features it is required that the passenger cars be brought to a normal stop at the proper position at each of the loading platforms regardless of the efficiency or physical alertness of the operator. In other words, if the operator becomes physically disabled or otherwise inattentive it is necessary to have the cars automatically stopped by the control in order to prevent an accident.

While there are several safety features incorporated in the control to bring the cars to a safe stop in case the operator fails to properly manipulate the control it is necessary to make this function automatic with respect to the position of the cars. Because of the high speed of the cars it is highly desirable to have two or more points of automatic slow-down prior to reaching the final limit position of the cars.

A suitable gearing 107 is interposed between the shaft of the driving sheave and one member of a differential gear 108, another member of the differential gear coupled to a screw 109 of the travelling nut limit switch. The third member of the differential gear 108 is directly coupled to a small reversing driving motor 111 equipped with a spring-set magnetic-release friction brake 112. Consequently, if the motor 111 remains

stationary the differential gear will drive directly through between the gear reduction 107 and the screw of the travelling nut switch 109. A dog 110 can travel along the screw 109 and operate any of the various toggle type switch units such as 113—114 or 123—128. When the screw of the limit switch is properly aligned with respect to the position of the passenger cars the dog 110 travelling on the screw 109 should be at position "A" when the passenger cars are brought to a stop at the proper place at the loading platforms. At this position of the switch the dog should engage the switch 114 so that the poles of the switches 118 are moved to their open position thereby disconnecting the motor 111 from the source of power 132—133—134.

Two track type limit switches 119 and 120 are located so that the passenger car will close the contact members 121 of switch 119 when the car 102 is brought to its proper position at the loading platforms illustrated by the dotted lines. Likewise switch 120 closes contact members 122 when car 101 reaches the position illustrated by the solid lines.

Assume that car 101 is brought to a proper stop at the upper loading platform (illustrated by the full lines) and assume that dog 110 is in an incorrect position as shown due to slippage between the cables and sheaves. Switch 120 thereby closes contact members 122 and a circuit is then completed from the supply line 131 to lower contact members 122, conductor 134, upper contact members 118, conductors 135, 136, thence to one terminal of motor 111. Another circuit is also completed from supply line 133 to upper contact members 122, conductor 137, lower contact members 118, conductors 138 and 144 to a second terminal of motor 111. The third terminal is directly fed by conductor 132. Assume that due to slipping of the cable on the driving sheave the dog 110 on the screw 109 stops at position "C" and, therefore, contact members 118 are closed. The circuit is then established to energize the motor 111 driving the control member of the differential gear 108. Since the sheave 104 is at standstill and the shaft driven by gearing 107 of the differential gear locks, rotation of the driving motor 111 will cause rotation of the screw 109. In this manner the screw will propel the dog 110 upwardly until switch 114 opens contact members 118 in order to stop the driving motor. The screw has then been corrected to the proper position and has compensated for slip of the cable 103 with respect to the driving sheave 104.

Had the error been in the opposite direction the dog may have been moved too far by the screw and have assumed such position as illustrated by "B." In this case the switch 114 would close contact members 117 and open contact members 118 thereby effecting a reversal of one of the incoming phase lines (136—134) and establishing a circuit to the driving motor 111 in the reverse direction and the screw 109 would be driven in a direction as to propel the dog 110 downwardly. In other words, the final position of the dog 110 will be midway between the position "AB" as shown.

Correction at the opposite limit of travel is made in exactly the same way by operation of the switch 119 closing the contact members 121 when car 102 reaches the position illustrated by the dotted lines, completing the power circuit to switches 115 and 116. The procedure is exactly analogous to that outlined previously.

Switches 123 and 124 are incorporated as a part of the control equipment for driving the motor 106 and are the switches which control the final position limit and will cause the motor 106 to stop if the dog 110 engages either of switches 123 or 124. It is important to note that these latter switches must be operated by travel of the dog 110 beyond the position which operates the switches 113 and 114, previously discussed. Therefore, when the cars are stopped in their proper position by the operator manually operating the control, neither of the switches 123 and 124 is engaged by the dog 110. However, if the operator fails to shut off the power driving motor 106 the dog 110 will operate either switch 123 or 124 which because of their series relationship with relay 143 will effect deenergization thereof and effect stopping of the motor 106 and the cars will come to rest slightly beyond the travel which they normally assume. However, this differential in travel need only be a few feet and there would be no danger in such operation.

Switches 125, 126 and 127, 128 are used to slow down the operating speed of driving motor 106 prior to reaching the final limit position. There are only two such switches shown, but in actual practice this number may be four or more. The function of the control would be in case the operator failed to slow down the motor 106 by operation of the manual control master switch engagement of dog 110 with switches 126, and 125 would deenergize relays 141 and 142, successively, thus inserting resistances 139 and 140, successively in the main motor circuit thus slowing down the speed of motor 106 and finally stopping the motor when the dog 110 reached the position "B" shown on the drawings that is after switch 123 has been actuated. The operation would be similar if the limit of travel were in the opposite direction in which event switches 127 and 128 effect operation of relays 141 and 142 respectively.

As shown in the drawings, the two tram cars 45 will be alternately moved from one of their respective terminal positions to the other of their respective terminal positions. In order to provide the reversing movement to the cable the motor 106 which is shown as a shunt wound, direct current motor, is reversely energized by reversely connecting the field winding 150 to the main power circuit through either of the two switches 151 or 152. The switches 151 and 152 are, in turn, selectively controlled by a controller switch 55 which is illustrated, for simplicity, as a single pole double throw switch. The armature circuit is illustrated as passing through contact members on either switch 151 or 152 so the motor circuit will be opened as both switches 151 and 152 are deenergized, when the master switch 155 is thrown to the neutral position.

In order to decelerate the main motor 106 as the tram cars 101 and 102 approach their respective terminal positions the motor circuit is appropriately controlled to reduce the motor speed. In practice, the system actually employed for that purpose is a variable voltage direct current system, but, for the sake of simplicity, I have illustrated a simple system in which the armature circuit is provided with two resistors 139 and 140 connected in series relationship and which are arranged to be progressively inserted into the armature circuit by deenergization of relays 141 and 142, respectively.

Since it is necessary in most cases to provide

a position indicator for indicating the position of the cars being operated, the equipment used to correct the screw of the travelling nut limit switch described above may also be used to correct the position of the indicator.

Referring to Figure 3, one method of accomplishing this would be to couple a gear reducer 129 of the proper ratio to the screw 109 of the travelling nut switch so as to operate a position indicator 130. The ratio of this gearing would be such that the full scale movement of the indicator would correspond to the movement of the cars for one trip. The position indicator may be directly coupled by some means of gearing illustrated or else it may be remotely operated by the conventional type of synchro-tie drive.

My invention is not limited to the details of the system illustrated, since they may be modified to achieve the same result without departing from the invention as set forth in the appended claims.

I claim as my invention:

1. In a tramway system, the combination with a driving motor, a sheave driven thereby, a traction rope driven by the sheave to operate a car, and a position indicator also driven by the motor to indicate the position of the car, of a differential mechanical connection between the motor and the position indicator to permit operation of the position indicator independently of the driving sheave to permit readjustment of the indicator relative to the sheave to compensate for slipping between the sheave and the traction rope and actuating means including the car itself for initiating said readjustment at terminal positions of said car.

2. A system as in claim 1, including an auxiliary motor that is provided to drive or to brake one element of the differential mechanical connection, and switching means directly controlled by the car at a terminal position of its path of travel for controlling the operation and direction of rotation of the auxiliary motor.

3. In a tramway system, in which a motor-operated sheave drives a traction rope to move a car back and forth along a predetermined path, and also drives a travelling nut position indicator, means for automatically correcting the position of the indicator for slip between the traction rope and the sheave, said means comprising a threaded actuator for the travelling nut indicator, a differential mechanical driving connection between the sheave and the threaded actuator for the indicator, a motor for driving or for holding stationary one element of the differential driving connection, and a pair of limit switches, one located at each end of the path of travel of the car and in a position to be directly operated by the car at each end of its travel, for controlling a circuit to the motor for the differential to cause the motor to operate the actuator to shift the indicator, if necessary, to correct for slippage between the sheave and the traction rope.

4. In a tramway system, in which a motor-operated sheave drives a traction rope to move a car back and forth along a predetermined path, and also drives a travelling nut position indicator, means for automatically correcting the position of the indicator for slip between the traction rope and the sheave, said means comprising a threaded actuator for the travelling nut indicator, a differential mechanical driving connection between the sheave and the threaded actuator for the indicator, a motor for driving or

for holding stationary one element of the differential driving connection, and a limit switch located at the end of the path of travel of the car and in a position to be directly operated by the car at the end of its travel, for controlling a circuit to the motor for the differential to cause the motor to operate the actuator to shift the indicator, if necessary, to correct for slippage between the sheave and the traction rope, and a limit switch operable by the position indicator for opening the circuit between the car limit switch and the differential motor, to prevent energization of the motor when the position indicator is in proper terminal position corresponding to car terminal position.

5. In a tramway system, in which a motor-operated sheave drives a traction rope to move a car back and forth along a predetermined path, and also drives a travelling nut position indicator, means for automatically correcting the position of the indicator for slip between the traction rope and the sheave, said means comprising a threaded actuator for the travelling nut indicator, a differential mechanical driving connection between the sheave and the threaded actuator for the indicator, a motor for driving or for holding stationary one element of the differential driving connection, a normally open limit switch closable by the car at terminal position, a normally closed limit switch operable by the position indicator at terminal positions, and means connecting the limit switches in series between a source of energy and the motor for the differential.

6. In a tramway system, in which a motor-operated sheave drives a traction rope to move a car back and forth along a predetermined path, and also drives a travelling nut position indicator, means for automatically correcting the position of the indicator for slip between the traction rope and the sheave, said means comprising a threaded actuator for the travelling nut indicator, a differential mechanical driving connection between the sheave and the threaded actuator for the indicator, a motor for driving or for holding stationary one element of the differential driving connection, two normally open limit switches, each operable by car-associated means when the car is at corresponding limit position of its path of travel, two normally closed limit switches, each operable by position-indicator-associated means when the indicator is at the corresponding limit position of its path of travel, a source of energy, and means connecting said source through said limit switches in series, respectively, to the motor for the differential to establish rotation of the motor in either direction to shift the position-indicator when necessary to compensate for slippage between the sheave and the traction rope.

7. In a tramway system, the combination with a driving motor, a sheave driven thereby, a traction rope driven by the sheave to operate a car, and a position indicator also driven by the motor to indicate the position of the car, of a differential mechanical connection between the motor and the position indicator to permit operation of the position indicator independently of the driving sheave to permit readjustment of the indicator relative to the sheave to compensate for slipping between the sheave and the traction rope, and means the operation of which is initiated by the car, itself, when at its terminal position for operating the differential connection to readjust the indicator relative to the sheave.

to compensate for slippage between the rope and the sheave.

8. In a tramway system, the combination with a driving motor, a sheave driven thereby, a traction rope driven by the sheave to operate a car, and a position indicator also driven by the motor to indicate the position of the car, of a differential mechanical connection between the motor and the position indicator to permit operation of the position indicator independently of the driving sheave to permit readjustment of the indicator relative to the sheave to compensate for slipping between the sheave and the traction rope, and means the operation of which is initiated by the car itself when at its terminal position for operating the differential connection to readjust the indicator relative to the sheave to compensate for slippage between the rope and the sheave, a reversible means for operating the differential connection to readjust the indicator relative to the sheave to compensate for slippage between the rope and the sheave and switch means controlled by the position indicator and by the car to selectively energize the reversible means.

9. In a tramway system, the combination with a driving motor, a sheave driven thereby, a traction rope driven by the sheave to operate a car, and a position indicator also driven by the motor to indicate the position of the car, of a differential mechanical connection between the motor and the position indicator to permit operation of the position indicator independently of the driving sheave to permit readjustment of the indicator relative to the sheave to compensate for slipping between the sheave and the traction rope, an auxiliary reversible motor operatively connected to drive one element of the differential mechanism other than that connected to the driving motor to operate the mechanism when the driving motor is stationary, and means including the car itself for energizing the auxiliary motor after the driving motor has moved the car to terminal position, and the driving motor is stationary.

10. In a tramway system, in combination, a car, a traction cable which has a portion thereof fastened to said car, a reversible driving motor, a sheave which is driven by said motor in one direction or another, depending upon the direction of rotation of said motor, to effect movement of said car in one direction or in an opposite direction; a mechanical differential gear system which is driven by said motor, a car-position indicator which is driven by said motor through said differential gear system, a second motor which also drives through said differential gear system for effecting adjustment of said indicator independently of said first-named driving motor, limit switch means which is adapted to be directly actuated by said car at the end of its travel for controlling said second motor and the position of said indicator to adjust for errors due to slippage between said sheave and said first driving motor.

11. In a tramway system, in combination, a car, a traction cable which has a portion thereof fastened to said car, a reversible driving motor, a sheave which is driven by said motor in one direction or another, depending upon the direction of rotation of said motor, to effect movement of said car in one direction or in an

opposite direction; a mechanical differential gear system which is driven by said motor, a car-position indicator which is driven by said motor through said differential gear system, a second motor which also drives through said differential gear system for effecting adjustment of said indicator independently of said first-named driving motor, a limit switch at the end of the path of travel of said car and which is adapted to be operated directly by said car to effect completion of a circuit through said second motor to effect movement of said indicator so as to compensate for errors due to slippage between said sheave and said first driving motor,

10 a longitudinally reciprocable switch actuating dog which is also driven through said mechanical differential gear system, switch means at the end of the normal travel of said dog which is actuated thereby for interrupting the circuit through said second motor to interrupt the corrective movement of said indicator.

12. In a tramway system, in combination, a car, a traction cable which has a portion thereof fastened to said car, a reversible driving motor, a sheave which is driven by said motor to effect movement of said car in one direction or in an opposite direction; a mechanical differential gear system which is driven by said motor, a car-position indicator which is driven by said motor through said differential gear system, a second motor which also drives through said differential gear system for effecting adjustment of said indicator independently of said first-named driving motor, a longitudinally reciprocable switch actuating dog which is also driven through said mechanical differential gear system, switch means beyond the end of the normal travel of said dog which is actuated thereby for effecting a slowing down, and upon further movement, a stopping of said first motor.

13. In a tramway system, in combination, a car, a traction cable which has a portion thereof fastened to said car, a reversible driving motor, a sheave which is driven by said motor to effect movement of said car in one direction or in an opposite direction; a mechanical differential gear system which is driven by said motor, a car-position indicator which is driven by said motor through said differential gear system, a second motor which also drives through said differential gear system for effecting adjustment of said indicator independently of said first-named driving motor, a limit switch at the end of the path of travel of said car and which is adapted to be directly operated by said car to effect completion of a circuit through said second motor to effect movement of said indicator so as to compensate for errors due to slippage between said sheave and said first driving motor, a longitudinally reciprocable switch actuating dog which is also driven through said mechanical differential gear system, switch means at the end of the normal travel of said dog which is actuated thereby for interrupting the circuit through said second motor to interrupt the corrective movement of said indicator and a second switch means at the end of the normal travel of said dog, also actuated by said dog for slowing down the speed of said first motor and upon further travel of said dog, effecting stopping of said first motor.

WALDEMAR I. BENDZ.
